Des. 214,545
Patented June 24, 1969

214,545

HEATER FOR INDIVIDUAL HAIR CURLERS

Anthony N. D'Elia, 355 Netherland Ave., Riverdale,
N.Y. 10471, and Edward M. Stolarz, R.F.D. 2,
Horton Drive, Yorktown Heights, N.Y. 10598

Filed Sept. 18, 1967, Ser. No. 8,622

Term of patent 3½ years

Int. Cl. D23—03; D28—03
U.S. Cl. D86—10

FIG. 1

FIG. 2

FIG. 4

FIG. 3

FIG. 1 is a front perspective view of a heater for individual hair curlers embodying our new design; the rear being identical;

FIG. 2 is a side elevational view thereof, the opposite side being identical;

FIG. 3 is a top plan view thereof; and

FIG. 4 is a bottom plan view thereof.

We claim:

The ornamental design for a heater for individual hair curlers, as shown and described.
